UNITED STATES PATENT OFFICE.

HENRY C. HOLLOWAY, OF GILROY, CALIFORNIA, ASSIGNOR OF ONE-HALF TO WILLIAM DE HART, OF WATSONVILLE, CALIFORNIA.

INTERNAL-COMBUSTION ENGINE.

No. 809,614.

Specification of Letters Patent.

Patented Jan. 9, 1906.

Application filed February 6, 1905. Serial No. 244,458.

To all whom it may concern:

Be it known that I, HENRY C. HOLLOWAY, a citizen of the United States, residing at Gilroy, in the county of Santa Clara and State of California, have invented new and useful Improvements in Internal-Combustion Engines, of which the following is a specification.

My invention relates to improvements in that class of engines known as "explosion" or "internal-combustion" engines.

It consists in a means for controlling the explosion or expansion of an impelling medium between an independent explosion or expansion chamber and the cylinder within which the piston travels.

It also comprises a combination of mechanism and details of construction, which will be more fully explained by reference to the accompanying drawings, in which—

20 Figure 1 is a section through my engine. Fig. 2 is a section through combustion-chamber.

It is the object of my invention to obtain a more perfect control for that class of engines which are known as "internal-combustion" or "explosion" engines and in which the expansion of an ignited gaseous vapor acts to impel a piston within a cylinder, and this control I effect by admitting the medium into an independent chamber wherein it is ignited and in providing connection between said chamber and the cylinder with a means for controlling this connection, and thus regulating the speed and power of the engine.

35 I have here illustrated my invention as applied to what is known as a "two-cycle" engine; but it will be manifest that it may also be applied to other forms of this class of engine.

40 As shown in the drawings, A is the cylinder, having the water-jacket B, or, if preferred, it may be air-cooled in the usual or well-known manner. Within the cylinder A the piston 2 is fitted with suitable packing-rings, and the piston-rod 3 connects it with a slide 4, movable in guides, as at 5. The connecting-rod 6 extends between the slide and the crank-pin, as at 7, and through this crank-motion is transmitted to the shaft, as at 8. I

45 have here shown the engine as having a head at the lower end of the cylinder and the stuffing-box, as at 9, through which the piston-rod passes. Upon one side of the cylinder as here shown is an inlet-passage 10, opening

into the cylinder from a valve-chamber 11, 55 and 12 is an inwardly-opening valve seating on the inside of the chamber 11 and normally closed by a spring, as at 13. The upward movement of the piston will draw a charge of the combustible vapor through the passage 60 10 and into the cylinder, the vacuum caused by the upward movement of the piston being sufficient to open the valve 12 against its spring-pressure. The chamber 11 is connected with any suitable carbureter or source 65 of supply. (Not here shown.) Upon the opposite side of the cylinder, and contiguous to the lower head thereof, is a passage 14 controlled by an outwardly-opening spring-pressed valve 15, which yields to the pressure 70 of the gas and automatically opens to admit the gas into a chamber 16 located upon that side.

The operation thus far is similar to that of a two-cycle engine, the upward movement of 75 the piston 2 drawing in a charge through the automatically-operated inlet-valve and compressing said charge through the outlet-valve 15 into the chamber 16.

From the chamber 16 a passage opens into 80 the combustion-chamber 18, and this passage is controlled by a valve, as at 19. This valve opens into the chamber 18 and is a mechanically-actuated valve having a stem, as at 20, the lower end of which is in line to be operated by the action of a cam 21, carried upon the shaft 22, which shaft is so located as to be driven from the engine-shaft 8 by intermediate gears and at such rate of speed as will coincide with the movements of the engine. 90 Thus when the engine is in operation the charges of gas compressed into the chamber 16 are admitted into the combustion-chamber 18 by the lifting of the valve 19, and as this valve closes outwardly it will not be opened 95 by the subsequent combustion and expansion of gas within the chamber 18. After the combustion and utilization of the gas within this chamber the waste products are expelled through an exhaust-valve, as at 23, opening 100 outwardly from the chamber and also actuated at the proper time by a cam upon the cam-shaft similar to that shown at 21.

Between the chamber 18 and the upper and working part of the cylinder A is a passage, 105 as at 24, this passage being of sufficient size to admit the maximum pressure to the cylinder. When this passage is opened; the ex-

pansion caused by the combustion of gas within the chamber 18 will be transmitted directly through the passage and the impulse given to the piston in the usual manner. Any suitable ignition device may be used connected with the chamber 18 and not here shown.

In order to control the action of the engine, I have shown a valve, as at 25, located between the chamber 18 and the working end 10 of the cylinder, and this valve may be connected with any suitable operating-lever or equivalent device, so that the amount of expanded gas and consequent pressure upon the piston may be regulated and the power and 15 speed of the engine thus controlled.

It will be understood that the combustion-chamber 18 will be sufficiently strong to resist any internal pressure which may occur from the explosions within the chamber, and 20 as the limit of such pressure can be easily determined when the initial compression within the chamber is known it will not be difficult to provide the necessary strength.

Having thus described my invention, what 25 I claim, and desire to secure by Letters Patent, is—

1. An internal-combustion engine comprising a cylinder closed at both ends, a piston, a piston-rod extending through the stuffing-box in one head, connecting with the cross-head and crank-shaft, inlet and outlet passages contiguous to the lower cylinder-head, automatically-operating valves by which gas is admitted to the cylinder and transmitted therefrom, said valves operated by and during the movement of the single power-piston, a receiver for the compressed gas, an independent combustion-chamber intermediate between said receiver and the cylinder, and a valve 30 controlling the transmission of gas from the receiver to the combustion-chamber.

2. An internal-combustion engine, comprising a cylinder having passages at opposite sides, a piston reciprocating in said cylinder, automatically-controlled inlet and outlet valves through which the impelling medium is transmitted by the movement of the piston, a receiver and a combustion-chamber above

the same with a valve between the two and operating in a plane parallel with the piston, 50 and a valve-controlled opening between the combustion-chamber and the working end of the cylinder.

3. In an internal-combustion engine, a cylinder, piston-passages at opposite sides of 55 the inner end of the cylinder said passages being essentially in line, automatically-operating valves through which the impelling medium is first drawn into the cylinder and then compressed and forced out, a receiving-chamber at one side of cylinder and into which the compressed gas passes, a combustion-chamber at one side of the cylinder and in line with the receiver and connecting with the receiver, and a mechanically-operated valve 60 movable in a plane parallel with the piston and through which the compressed gas is admitted to the combustion-chamber, a passage between the combustion-chamber and the working end of the cylinder, and a manually-operated valve 70 controlling said passage.

4. In an internal-combustion engine, a cylinder with reciprocating piston, inlet and outlet valves communicating with opposite sides of the lower end of the cylinder, a receiver on 75 the outside of the cylinder and into which the impelling medium is compressed by the reciprocations of the engine-piston and the opening of said valves, a combustion-chamber on the outside of the cylinder in line with the receiver and intermediate between the receiver and the working end of the cylinder, a mechanically-operating valve through which the compressed gas is delivered to the combustion-chamber, a port opening from the combustion-chamber into the working end of the cylinder, 80 a valve controlling the passage through said port and a mechanically-actuated exhaust-valve connecting with the combustion-chamber. 90

In testimony whereof I have hereunto set my hand in presence of two subscribing witnesses:

HENRY C. HOLLOWAY.
